UNITED STATES PATENT OFFICE

ERNST BERL, OF DARMSTADT, GERMANY

FILLING BODY FOR REACTION AND WASHING TOWERS

Application filed August 31, 1929, Serial No. 389,770, and in Germany September 18, 1928.

For filling reaction and washing towers and the like a large series of different filling bodies of the most diverse geometrical shape and constructed of the most diverse materials have been suggested previously. Such filling bodies can be inserted into the reaction body either in a regular arrangement or may be arranged therein irregularly.

It has now been found that a saddle like shape of the reaction bodies is very suitable and produces a particularly large washing surface. It is particularly advantageous if these shapes are so selected that they are substantially as wide as they are high. It has also been found of particular advantage to provide the saddle shaped bodies either with discharging grooves or with holes or with both. For this purpose they may for example be constructed of wire netting. According to a further form of construction of the invention the shapes, by means of suitable operations, as for example by slightly pressing together the ends or by the application of suitable projections, ribs or the like, may also be so shaped that the reaction bodies are prevented from sliding one into the other. Two or more suitably shaped bodies placed parallel to one another and at a predetermined distance apart may also be assembled to form a single unit.

In the accompanying drawing are illustrated by way of example a few forms of construction of the filling bodies according to the present invention.

Figures 1 to 4 show saddle shaped filling bodies having substantially the same dimensions in length and width. Figure 1 is a front elevation, Figure 2 a side elevation, Figure 3 a plan and Figure 4 a section on the line A—B of Figure 3.

Figures 5 to 8 show a filling body provided with small projections. Figure 5 shows a front elevation, Figure 6 a side elevation, Figure 7 a plan and Figure 8 a section on the line C—D of Figure 7.

Figures 9 to 12 show a filling body provided with ribs. Figure 9 is a front elevation, Figure 10 a side elevation, Figure 11 a plan and Figure 12 a section on the line E—F of Figure 11.

Figures 13 to 16 show a filling body having its ends pressed slightly towards one another. Figure 13 shows a front elevation, Figure 14 a side elevation, Figure 15 a plan and Figure 16 a section on the line G—H of Figure 15.

Figures 17 to 20 show two filling bodies assembled as a single unit. Figure 17 is a front elevation, Figure 18 a side elevation, Figure 19 a plan and Figure 20 a section on the line J—K of Figure 19.

Referring now more particularly to the accompanying drawings there is provided a filling body *a* having the shape of a riding saddle. The body is formed from a circular blank which is folded upon itself in arcuate formation to form the downwardly bent lugs *b* and *b'* which correspond to the saddle leaves and reversely folded in a plane at right angles to the first fold to provide two upwardly bent lugs *c* and *c'* which correspond to the front pad and rear pads of the saddle seat. In other words the circular body is subjected to a crosswise reversed compressing or folding.

On the curved inner surface of the constructional forms according to Figs. 1—4, holes are provided at certain distances apart while the constructional forms according to Figures 5—8 show pegs *e* provided on the saddle face. Figures 9—12 show constructional forms provided with ribs *f* and Figures 13—16 with parallel grooves *g*. The last named group shows that the primary shape may also be modified in that the lugs bent in crosswise opposite directions are more or less pressed together. Fig. 15 shows how the two lugs *c* and *c'* are relatively compressed in their center. The filling body according to Figs. 17—20 comprises two single bodies *a* and *a'* and is formed by uniting two single bodies on corresponding flanged faces.

It has been found that filling bodies of the present invention which show as primary shape a crosswise reversed compressed circular area of a form resembling a riding saddle occupy considerably less space and have a much larger working surface. Filling bodies according to the invention have especially the advantage that they do not re-

- quire to be regularly fitted into the reaction chambers as according to the hitherto usual geometrical molded bodies but may be loosely and irregularly filled in. The attainable reaction surface is almost double and if necessary more than double the surfaces attainable with the usual filling bodies. The very thin structure also permits a very tight and secure fitting in the reaction vessels. Owing to the peculiar saddle shape the gas streams are continually deflected and always come in contact with irrigated surfaces—an action or effect which could only be very inadequately attained with the usual types. For instance, in cylinder bodies the gases rise within the cylinder and occupy the upper positions while the liquid moves on to the lowest positions and is thereby only in inadequate contact with the gas.
- Such saddle shaped reaction bodies may be placed into the chamber in an irregular manner. They form an extremely large surface and, by reason of the constant change in direction in the flow of streams of gas or liquid, an excellent means for promoting chemical and physical operations such as increasing the speed of reaction on stationary surfaces, extraction and mixing operations between liquids and liquids, between liquids and gases and between gases and gases in the most favourable manner.

The reaction bodies themselves may be constructed of the most diverse material according to chemical and mechanical requirements and may also be constructed in different sizes.

I claim:—

1. A filling body for reaction and washing towers and the like, formed from a circular blank folded in a crosswise reversed manner to resemble a riding saddle, the height and breadth being substantially equal.
2. A filling body according to claim 1 having apertures therein.
3. A filling body according to claim 1 wherein the saddle portion is provided with enlargements.
4. A filling body according to claim 1 wherein the opposed folded portions are slightly bent towards one another adjacent their outer edges.
5. A filling body for reaction and washing towers and the like comprising a plurality of saddle shaped elements assembled parallel to one another and held at suitable distances apart, the saddle shaped elements forming an integral unit.

In testimony whereof I affix my signature.
PROF. DR. ERNST BERL.
